United States Patent Office

Des. 212,389
Patented Oct. 8, 1968

212,389

GUITAR OR SIMILAR ARTICLE

Vincent Gambella, Tenafly, and Nathan I. Daniel, Deal, N.J., assignors, by mesne assignments, to The Danelectro Corporation, Neptune City, N.J., a corporation of New York

Filed July 11, 1967, Ser. No. 7,759

Term of patent 14 years

(Cl. D56—1)

The single figure is a top perspective view of a guitar or similar article showing our new design.

Portions of the figure are lined for transparency. The back of the guitar is a flat unornamented surface.

We claim:

The ornamental design for a guitar or similar article, as shown and described.
